Primary Examiner — Jae Liang*Assistant Examiner* — Tia Ruth-Renee Polidori(74) *Attorney, Agent, or Firm* — MH2 Technology Law Group LLP(57) **CLAIM**

The ornamental design for a textile machine, as shown and described.

DESCRIPTION

FIG. 1 is a perspective view of a textile machine;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

The broken lines in the drawings depict portions of the textile machine that form no part of the claimed design.
